UNITED STATES PATENT OFFICE.

DAVID ALEXANDER BRITTAI, OF WESTFIELD, CANADA.

SKIDDING-TONGS.

SPECIFICATION forming part of Letters Patent No. 673,356, dated April 30, 1901.

Application filed May 16, 1900. Serial No. 16,891. (No model.)

To all whom it may concern:

Be it known that I, DAVID ALEXANDER BRITTAI, a subject of Her Majesty the Queen of Great Britain, residing at Westfield, county 5 of Kings, Province of New Brunswick, Canada, have invented certain new and useful Improvements in Skidding-Tongs; and I do hereby declare that the following is a full, clear, and exact description of the invention, such 10 as will enable others skilled in the art to which it appertains to make and use the same.

My invention relates to improvements in skidding-tongs especially adapted to be used in lumbering regions for handling logs and 15 timber of all kinds and for loading and unloading lumber on ships.

The ordinary skidding-tongs consist principally of a pair of members pivoted together and having means for the attachment of a 20 haulage cable or chain; but such devices are open to the serious objection that they release the log or other piece of work when the cable or chain slackens, thus releasing the log and allowing it to drop, which sometimes is attended with serious results, besides involving 25 loss of time. I aim to overcome these objections by providing the skidding-tongs with a locking mechanism which effectually prevents the tongs members from movement relative to each other during the operation of hauling or lifting the log, which locking device is arranged for easy and convenient manipulation. Said locking device is simple 30 in construction, may be applied to the ordinary or any preferred style of tongs used for skidding lumber, and is efficient and reliable in operation.

Further objects and advantages of the invention will appear in the course of the subjoined description, and the novelty in the construction and arrangement of parts will be defined by the claims.

In the drawings hereto annexed and forming a part of this specification, Figure 1 is a 45 side elevation of my improved skidding-tongs. Fig. 2 is an edge view thereof. Fig. 3 is a sectional view on the plane of the dotted line 3-3 of Fig. 1. Fig. 4 is a face view of the boxing removed from one member of the tongs 50 and illustrating the preferred form of locking-dog.

The same numerals of reference are used

to indicate like parts in each of the several figures of the drawings.

10 11 designate the members of a pair of 55 skidding-tongs, which members are fashioned, as shown by Fig. 1, to provide the short arms 12. These arms cross or overlap each other and are pivotally connected, as at 13. The other ends of the tongs members are provided 60 with the inwardly-extending prongs 14.

As thus far described the tongs are similar to devices well known in the art, and I will now proceed to describe the improvement which I have made. 65

15 designates the segment, which constitutes one element of my locking mechanism, which segment is applied to one member of the tongs. I prefer to form the end portions of this segment with the forks or bifurcations 16, which 70 are applied to the member 10 of the tongs at points equidistant from the pivot 13, whereby the segment is arranged in a position concentric with the pivot, which constitutes the axis of motion of the tongs members. The forked 75 end portions of the segment may be secured firmly to the member 10 by any suitable fasteners, such as the rivets or screws 17, and this segment is provided on its inner edge with a continuous series of ratchet-teeth 18. 80 Another member of my locking mechanism is the boxing 19, adapted to support the locking-dog 23, and this boxing is fastened securely in any approved way to the other member 11 of the tongs. This boxing is shown 85 more clearly by Figs. 3 and 4 as being cast in a single piece of metal, and it is provided with a transverse recess or slot 20 and the longitudinal guideway 21, one end of the latter opening into a notch 22, which is formed in 90 one end of the boxing. This boxing may be fastened to the member 11 by screws, rivets, or equivalent fastenings, and it is arranged on said member for its transverse slot or recess 20 to loosely receive the segment 15, 95 whereby the members of the tongs may be opened or closed freely when the locking-dog 23 is disengaged from the ratchet-teeth on the inner edge of the segment. This locking-dog constitutes another element of my locking 100 mechanism, and in the preferred form of this dog it is slidably fitted in the guideway 21 for movement within the boxing toward and from the toothed edge of the segment. Said

11 12 13 14 15 16 17 18 19 20 21 22 23 24 25 26 27 28 29 30 31 32 33 34 35 36 37 38 39 40 41 42 43 44 45 46 47 48 49 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100

locking-dog is provided at one end with the serrated face 24, which forms a number of points for engagement of the dog with a corresponding number of the ratchet-teeth on the 5 segment, whereby the dog may be securely engaged with the segment against the possibility of slipping. This locking-dog is provided with a longitudinal slot 25, which forms a shank 26, the latter terminating in an arm 10 27, that extends outwardly from the dog. This arm is arranged to fit in the notch 22 of the boxing when the dog is pressed into engagement with the segment by the action of a spring 29, the latter being seated at one end 15 on a shoulder 28 of the boxing and having its opposite end disposed in operative relation to the dog. The arm 27 of said dog is long enough to project beyond the face of the boxing, whereby the end of the arm forms a thumb-piece 20 for the convenient adjustment of the dog to retract the latter from engagement with the segment and overcome the tension of the impelling-spring 29.

The links 30 are loosely connected to the 25 upper ends of the short arms 12, and said links are connected by a ring 31. A swivel 32 forms an operative connection between the ring 31 and a haulage cable or chain 33.

In using the tongs the operator retracts the 30 dog from engagement with the segment, and the tongs are then opened to the desired extent. The pronged ends of the tongs are now engaged firmly with the log or piece of timber, and the dog is released, so that its spring 35 will impel it into engagement with the toothed edge of the segment. The locking mechanism prevents the members of the tongs from having movement relative to each other during the operation of hauling or lifting the log. 40 By my improvement the tongs remain firmly in engagement with the work to prevent the releasing thereof in the event of the cable or chain becoming slackened, and the improved implement firmly grips the log under all conditions of service and until the dog is again retracted by hand from the segment for the 45 purpose of discharging the load.

The members of the tongs may be made of steel; but I prefer to cast the boxing and the 50 slideable dog each in a single piece of metal. The segment may be made of steel or of cast

metal. The locking mechanism which I have devised may be applied to new tongs at the time of their manufacture; but the improvements are of such nature that they may be 55 readily applied to tongs already in use.

Changes within the scope of the appended claims may be made in the form and proportion of some of the parts, while their essential features are retained and the spirit of the 60 invention is embodied. Hence I do not desire to be limited to the precise form of all the parts as shown, reserving the right to vary therefrom.

Having thus described my invention, what 65 I claim as new is—

1. Skidding-tongs comprising pivoted members, a toothed segment secured at its ends firmly to one member on opposite sides of the pivot, a slotted guide-boxing fastened to the 70 other member and loosely embracing the segment, and a locking-dog slidably mounted in the boxing, and having a series of teeth adapted for engagement with a like series of teeth on the segment, substantially as described. 75

2. Skidding-tongs comprising pivoted members, a boxing secured firmly to one member and provided with a transverse slot and with a longitudinal guideway, a toothed segment fastened to the other member and passing 80 through the transverse slot of the boxing, and a spring-actuated dog slidably mounted in the guideway of the boxing and having a series of teeth arranged for engagement with a like series on the segment, substantially as de- 85 scribed.

3. Skidding-tongs comprising pivoted members, a boxing fastened securely to one member and having a shoulder and a notch, a toothed segment fastened to the other mem- 90 ber and fitted loosely in the boxing, a slideable dog mounted in the boxing and having at one end a serrated face and at its other end an extended arm, and a spring seated on the shoulder of the boxing and operatively disposed to the dog, substantially as described. 95

In witness whereof I have hereunto set my hand in the presence of two witnesses.

DAVID ALEXANDER BRITAIN.
